UNITED STATES PATENT OFFICE.

HAROLD WILLIAM HODGSON, OF WORCESTER, MASSACHUSETTS.

WIRe-DRAWING MACHINE.

1,390,714.

Specification of Letters Patent. Patented Sept. 13, 1921.

Application filed June 19, 1920. Serial No. 390,149.

To all whom it may concern:

Be it known that I, HAROLD WILLIAM HODGSON, a subject of the King of Great Britain, residing at Worcester, in the county 5 of Worcester and State of Massachusetts, have invented a new and useful Wire-Drawing Machine, of which the following is a specification.

This invention relates to a wire-drawing 10 machine in which the wire is drawn through one or more dies by a corresponding number of drums and then finally wound on a block.

There has been difficulty in the operation 15 of these machines owing to the fact that the friction of the wire in winding, and especially the working of its surface in the wire-drawing dies, increases the temperature of the wire very materially. This can not be 20 reduced to its original temperature from one drum to the next, although these drums are designed to work in water in some types of machines.

The principal object of this invention is 25 to provide efficient means for cooling the drums individually and efficiently and also the block, so designed that the cooling water will not remain in contact with the part to be cooled for any considerable time after it 30 has taken up the heat therefrom, thus increasing the efficiency of the cooling action.

Further objects and advantages of the invention will appear hereinafter.

Reference is to be had to the accompanying 35 drawings, in which—

Figure 1 is a side view of a part of a continuous wire-drawing machine, showing a preferred embodiment of this invention applied thereto;

Fig. 2 is a central sectional enlarged view 40 of one of the drums; and

Fig. 3 is a similar view of the winding block also having the invention applied thereto.

Although the invention can be applied to 45 other types of wire-drawing machines, it is especially valuable on the continuous type, involving a plurality of die holders 10, provided with dies through which the wire is

drawn. The wire is received from each of the dies, excepting the last one, on drawing drums 12, around which it passes one or more times and then is delivered to the next die. From the final die the wire passes on 50 a conical winding block or drawing-through drum 13 on which it is wound.

The present invention when applied to a machine of this type, involves the making of the drum 12 or the block 13 hollow at the bottom with an upstanding internal flange 60 15 to provide an annular space 16 just back of the winding circumference of the drum or block to hold some water for cooling purposes. Below the drum is a stationary receiver 17 having a circular flange 18 outside 65 of the bottom of the drum or block as the case may be, which also serves as a guard to keep the wire from running off the drum. It also has a circular internal flange 19 extending up just inside the flange 15 and 70 preferably substantially to the top thereof, at least. Through the interior of this receiver extends a water pipe 20 which bends up over the tops of the two flanges 19 and 15 and delivers water into the annular water 75 receiving space 16. This water, obviously, is located in the best position for effecting the cooling of the drum as the rotation of the drum forces it outwardly into a position to take up heat directly from the surface on 80 which the wire is wound. Its other two walls are connected to the wall behind that surface so that the conduction of heat into the water is facilitated all around the drum and all around the annular space. An outlet pipe 22 regulates the normal height of water in the space 16 and discharges into the receiver 17.

The water is run into the space 16 continuously at such rate as may be necessary 90 in view of the particular character of wire and the amount by which it is being modified in the dies. It then continuously overflows through the pipe 22. The wall 15 is located all around the interior so as to prevent overflow inwardly when the drum stops and the water previously held outwardly by centrifugal force flows inwardly. The water may be drained from the receiver 17 in any desired way and I have shown drain perforations 21 for that purpose. The top of the drum is shown as having a hand hole 23 through which the pipe 20 can be manipulated.

The invention is applied to the block or 105 drawing-through drum 13 in exactly the same way, as shown in Fig. 3, and no further explanation of that feature, therefore, is necessary. It is to be noted that the conical wall 25 which receives the wire throughout 110 the greater part of its length is not in contact with the water throughout its whole

height but as in the other case, integral metal walls connect the wall on which the wire is wound with the water receiving space and conduct the heat therefrom readily and freely.

No description of the operation of the wire-drawing machine is given as it can be worked in any of the ordinary ways, but the cooling operation is intended to be continuous so that the heating of the wire will not be cumulative. In this way, the wire can be drawn through a series of dies and wound continuously with less danger of injury by over-heating than has been the case heretofore and the operation can be carried out more rapidly, thus increasing the product.

Although I have illustrated and described the invention in a single form only, and as applied only to the drum and block, I am aware of the fact that modifications can be made therein by any person skilled in the art without departing from the scope of the invention as expressed in the claims. Therefore, I do not wish to be limited to all the details of construction or to the particular mode of applying it to the drum and block herein shown and described, but what I do claim is:—

30 1. In a wire drawing machine, the combination with rotary means for receiving wire from a die and drawing it therethrough, of means constituting part thereof for holding water in a position to be directed against 35 the interior surfaces of said rotary means by centrifugal force as the rotary means rotates.

2. A wire drawing machine having a wire winding means mounted to rotate and to draw the wire through a die to its own sur-

face, said means carrying a water space in 40 its interior just behind the wire receiving surface thereof and adapted to absorb heat therefrom, said space constituting a part of the drum."

3. A continuous wire drawing machine 45 comprising a wire winding drum mounted to rotate and to draw the wire through a die to its own surface and having walls forming a water space in the interior of said drum just behind the wire receiving surface thereof and in position to conduct heat therefrom, and means for introducing water into said water receiving space.

4. A wire drawing machine having a wire winding drum mounted to rotate and to 55 draw the wire through a die to its own surface, said drum having a water space formed as a part of it in its interior just behind the wire receiving surface thereof, and a stationary receiver below it having a space 60 located in position to receive water overflowing from the first named space and carry it off.

5. In a continuous wire drawing machine, the combination with a rotary drum for receiving wire from a die and drawing it therethrough, said drum having a flat circular flange extending inwardly from the bottom of its wire receiving surface and an upwardly extending internal flange at the 70 inner edge of said flat flange forming a water holding space in the drum, of means for continuously supplying water to said space.

In testimony whereof I have hereunto 75 affixed my signature.

HAROLD WILLIAM HODGSON.
